UNITED STATES PATENT OFFICE.

CLARENCE T. MAPES, OF PITTSBURGH, PENNSYLVANIA

UNDERREAMER.

Application filed November 8, 1922. Serial No. 599,652.

This invention is for an underreamer for use in earth boring, and relates to that type of underreamer having bits or cutters carried at the lower end thereof, which cutters are expanded from a collapsed position by a combined longitudinal and rocking movement.

The invention has for its principal objects to provide an underreamer of this type in which all the parts are of extremely simple design, eliminating many of the expensive machining operations necessary with the manufacture of some underreamers now on the market, but which has greater strength than some other tools of this type now on the market.

Other objects of the invention are to provide a one-piece body construction for the tool, a novel form of actuating mandrel for the cutters, and a novel form of cutter of great strength, all combined to co-act in providing a superior underreamer which may be easily assembled and taken apart.

These and other objects and advantages are attained by my invention, which is illustrated in the accompanying drawings, in which:

Fig. 1 is a side elevation of the assembled tool;

Fig. 2 is a longitudinal section on a larger scale of the tool shown in Fig. 1, with the cutting bits in expanded position;

Fig. 3 is a view similar to Fig. 2, with cutters in collapsed position;

Fig. 4 is a transverse section in the plane of line IV—IV of Fig. 2;

Fig. 5 is an end view of the cutting end of the tool;

Fig. 6 is a side elevation of the cutter actuating mandrel;

Fig. 7 is a fragmentary view, showing the lower end of the cutter in section as in Fig. 2, the section being in the plane of line VII—VII of Fig. 2;

Fig. 8 is a section similar to Fig. 7, showing the cutters removed;

Fig. 9 is an end view of the lower end of the body with the cutters removed;

Fig. 10 is a section in the plane of line X—X of Fig. 8;

Fig. 11 is a side elevation of the two cutters apart from the body;

Fig. 12 is a similar view of the cutters, showing them turned at right angles to the position in Fig. 11;

Fig. 13 is a perspective view of one of the cutters.

In the drawings, 5 designates a one-piece underreamer body having a threaded connection 6 at its upper end for joining the body to a tool string, and at 7, the body is flat-sided for accommodation of a wrench. The portion of the body below part 7 is cylindrical, and comprises the main part of the body.

The lower end of this cylindrical body portion is provided with an inwardly tapering or conical chamber 8, which is substantially circular at any point in cross-section, a chamber of this shape being readily formed in the body by a lathe operation. At diametrically opposite points in the conical walls of this chamber, and spaced inwardly from the bottom edge, which is continuously circular and without projecting lugs, are two recesses or pockets 9. These pockets can be readily formed in the walls of the chamber after the chamber has been machined in the body by a simple milling operation.

As contrasted with the remaining area of the walls of the chamber, the pockets do not taper inwardly, as clearly shown in Fig. 2. They are curved in transverse cross section, but they are struck on an arc whose radius is shorter than the radius of the chamber at the point where they are located, as will be apparent from Fig. 10.

The tapered chamber terminates in the body at shoulder 11, and from this point a longitudinal bore 12 extends for a considerable distance into the body. Passing through the body in a plane at right angles to the recesses 9, and intersecting the bore 12, are two parallel key slots 13.

The extreme lower end of the body is preferably beveled outwardly, as designated by 14.

Received within the body is a longitudinally movable mandrel 15 having a circular head 16 on its lower end, above which are two tapered keys 17. A short distance above the head is an enlarged portion 18 which is preferably of substantially the same diameter as the bore 12, so that it has a sliding fit therein. The stem of the mandrel above the enlarged portion has flat faces 19 on two diametrically opposite sides thereof, and the upper end of the mandrel is threaded at 20 to receive a nut 21. Shoulders 18^a are formed on the mandrel above the enlarged

part 18 thereof. The nut 21 serves to confine a compressing spring 22 between it and the shoulders 18^a, this spring surrounding the stem of the mandrel.

5 When the mandrel is in place in the body, it being readily removable therefrom, keys 23 are passed through slots 13 at each side of the mandrel, the keys bearing against the flat sides 19 of the mandrel to hold it from rotating. These keys are held in place by reason of the slots being tapered toward one end thereof, screws 24 (see Fig. 4) serving to hold the keys against reverse movement.

15 To insert the keys, a pilot key, not shown, but of usual construction, is first driven through the slots to raise spring 22 off from shoulders 18^a. The keys 23 follow the pilot keys, and when inserted form a seat against which the spring reacts for forcing the mandrel upwardly for the purpose hereinafter described.

25 The mandrel serves to retain and actuate a pair of opposed cutters, which cutters are designated 25. Each cutter comprises a bit portion 25^a and a shank 25^b.

30 The bit portion of each cutter has a cutting edge 26 and increases in cross section toward the upper part thereof by reason of the curvature of the inner face thereof. This cutter portion terminates at shoulder 27, which is inwardly beveled at 28. The cutter portion is substantially semi-circular in cross section, but it is turned in such manner that the center of curvature for lower part 29 is different from the center of curvature of upper part 30. In other words while the periphery of the cutter part is curved to comprise an arc of a circle at 35 any point, so as to be capable of being formed on a lathe, yet the axis of rotation about which the cutter is revolved in turning is different in the two parts designated 29 and 30 of the cutter. The cutter part of the bit is flattened at 31, and further flattened or cut away at 32.

35 As shown in Figs. 11 and 12, the shanks of the two cutters, when the cutters are set in expanded position, form a perfect truncated cone. Each shank is semi-circular in cross section at any point except where flattened surfaces 33 are formed on the inner faces of the shanks. When the cutters are expanded, they contact with each other throughout substantially the full area of 40 their opposing faces, except where they are drilled at 34 to loosely receive the mandrel and counter-bored at 34^a to receive the head of the mandrel, the faces 33 then being out of contact. When the cutters are collapsed, only faces 33 contact. Edges 35 are the edges on which the cutters rock on each other.

45 The shanks of the cutters may be turned in a lathe, the peripheries being semi-circu-

lar, but the axis about which they rotate is being turned is different, and angularly disposed with relation to the axis about which the major portion of the cutter is rotated in being turned down. The upper part of the shank is made to fit into the recesses 9, and the end face 36 of the shank conforms with the shape of and co-acts with the end shoulder 9^a of the recess. Cut into the channel 34 is a slot 37 for the reception of key 17 on the mandrel.

50 The cutters are held in the tool by means of the mandrel. The circular head 16 of the mandrel is received in recesses 34^a of the shank, while the stem of the mandrel passes up between the cutters. The top-ends of the shank, when the bits are collapsed, are received in the respective pockets 9. Keys 17 hold the cutters from rotation relatively to the mandrel, and keys 23 hold the mandrel 55 from turning. When the cutters are collapsed, the ends 36 of the shanks bear against shoulders 9^a. With the bits in this position, the mandrel is held down with the spring 22 under compression. In this position, the exterior faces of the cutter part 25^a of the bits are within the diameter of the body, and faces 33 of the shanks are in contact. In order to hold the bits in this position, they must be so confined as to hold 60 them from spreading. In practice, the well casing holds them against such expansion.

55 When the cutters are released, as by passing out of the end of the casing, the mandrel 15 is moved upwardly by the spring 22, imparting a corresponding motion to the bits 25. In order for the bits to slide, faces 9^a are inclined, and they act with surface 36 of the cutters as cams to throw the shanks of the bits into contact with each other, the 65 bits rocking on each other at point 35.

60 When the shanks of the bits are thus in contact with each other, they clear the recesses 9 and the bits may move further up into the chamber. The shanks form a substantially solid metal cone which wedges into the tapered chamber, the inner faces of the shanks bearing against each other while the ends of the chambers form shoulders which 70 abut against shoulder 11, and the outer faces of the shanks contact with the conical walls of the chamber 8, with which they conform. The beveled faces 28 of the cutters cooperate with the beveled end 14 of the cutter body.

75 The co-acting bevel faces 14 and 28 serve to deflect the otherwise unsupported vertical thrust of the working bits inwardly, decreasing the spreading or bursting strain on the extreme lower part of the body, and transmit it inwardly, where it is distributed over the large area of the walls of the conical recess away from the end of the body where the body can withstand it. By reason of the 80 shanks of the cutters forming a perfect cone,

the strains are distributed over a wide area, instead of being concentrated at two diametrically opposite points, and the strain is carried well up into the body of the tool, thus counteracting the spreading strains on the lower end of the body. The shanks of the cutters being in contact also transmit strains from the inner end of one bit to the inner end of the other. The round cross head 16 gives a full support to the cutters, while providing a very cheap form of support. The shanks of the cutters, being semi-circular, have a large cross section of metal therein, which greatly strengthens the bit.

15 When the conical shanks of the cutters are in working position, they act to exclude dirt from the bore and spring. The circular enlargement 18 also acts to exclude dirt. The spring 22 is so proportioned that, if, in pulling the tool, the bits 25 should catch instead of immediately collapsing, and the cutters thus be pulled down below the normal collapsed position of the cutters, the adjacent convolutions of the spring will make a metal 25 to metal contact, preventing mandrel head 16 from being pulled down so far as to allow the cutters to fall out. The only way, therefore, to remove the bits, is to remove keys 23.

As practically all of the shaping of the body and cutters may be carried out in a lathe, the tool is extremely simple and economical to make, and the very features that make for economy of manufacture also make for increased strength and duralibity.

35 I claim as my invention:

1. An underreamer comprising a one-piece body having a longitudinally extending bore formed in the lower part thereof and a bit receiving chamber at the extreme lower part 40 of the body into which the bore opens, a mandrel in said bore having a bit engaging head thereon which extends into the chamber, bits having shanks thereon, which shanks extend into the chamber, said bits 45 having recesses therein in which said head engages for supporting the bits, a circular enlargement on said mandrel having a sliding fit in the bore, said mandrel having flat faces formed thereon above the enlargement, 50 keys passing through the body engaging the flat sides of the mandrel, and a spring surrounding the mandrel confined between the keys and means at the upper end of the mandrel, the wall of said bit-receiving chamber having pockets therein for engagement by the bits in their collapsed condition, and interengaging means between the mandrel and bits to prevent turning of the latter independently of the mandrel so that 55 they may operate and may be maintained in proper lines with the pockets.

2. An underreamer including a body having a bore whose lower portion is frusto-conical and open and constitutes a bit-receiving chamber, a plurality of bits extend-

ing into said chamber, a mandrel non-rotatable relatively to said body, an operating spring in said body urging sliding movement of the mandrel to move the bits to operative position, the wall of said chamber being 70 continuous and having pockets corresponding in number to the bits for engagement by the bits in their collapsed condition, and interengaging means between the mandrel and the bits to maintain the bits in their 75 collapsed condition in line with the pockets so that they may be freely moved into the latter and to prevent rotation of the bits relatively to the mandrel and body.

3. An underreamer including a body having a central bore and a conical chamber in the lower end of the body, the wall of the chamber having a pair of opposed pockets therein, a pair of cutters having shanks projecting into the said chamber and which fit 80 together to form a substantially perfect truncated cone conforming to the said chamber in the body, the said shanks when the cutters are in operative position making contact with the conical walls of the chamber 85 over their entire unbroken surface, said pockets serving to receive the upper end of the shanks when the cutters are collapsed, and a mandrel non-rotatable relatively to the body for operating the cutters, and 90 means retaining the cutters against displacement relatively to the mandrel and accordingly against rotation relatively to the body.

4. An underreamer including a body having a central bore and a conical chamber 100 in the lowermost end of the body with the larger end of the conical chamber terminating at the bottom of the body, the wall of the chamber having a pair of opposed recesses therein between the upper and lower 105 limits of the chamber, a pair of cutters having shanks projecting into the conical chamber and which fit together to form a substantially perfect truncated cone conforming to the conical chamber in the body, the 110 said shanks when the cutters are in operative position contacting with the conical wall of the chamber over its entire unbroken surface, said pockets serving to receive the upper ends of the shanks when the cutters are 115 collapsed, and means non-rotatable relative to the body for moving the cutters to operative position, and interengaging connections between the latter means and cutters to hold the cutters against rotation relative 120 to the body and in proper alignment with respect to the pockets.

5. An underreamer including a body having a central bore and a conical chamber in the lowermost end of the body, with the larger end of the conical chamber terminating at the bottom of the body, the wall of the chamber having a pair of opposed pockets therein between the upper and the lower limits of the chamber and having a 125 130

continuous beveled lower extremity, a pair of cutters having shanks projecting into the conical chamber and which fit together to form a substantially perfect truncated cone conforming to the conical chamber in the body, the said shanks when the cutters are in operative position contacting with the conical wall of the chamber over its entire unbroken surface, said pockets serving to receive the upper ends of the shanks when the cutters are collapsed, said cutters having beveled shoulders thereon formed between the shank and the body portion to receive the beveled end of the body when the cutters are in operative position, and a mandrel non-rotatable relative to the body to hold the cutters against rotation relatively to the body and for operating the cutters.

In testimony whereof I affix my signature. 20

CLARENCE T. MAPES.
